[57] CLAIM

The ornamental design for a combined letter tray and step file, substantially as shown and described.

DESCRIPTION

FIG. 1 is a perspective view of a combined letter tray and step file embodying my new design;
FIG. 2 is a top plan view thereof;
FIG. 3 is a left side elevational view thereof, the opposite side being a mirror image thereof;
FIG. 4 is a front elevational view thereof;
FIG. 5 is a rear elevational view thereof; and
FIG. 6 is a bottom plan view thereof.
